UNITED STATES PATENT OFFICE.

WALTER H. WILKINSON AND HORACE L. GEE, OF KINGSTON, NEW YORK,
ASSIGNORS TO THE DIAMOND TRUCK AND CAR GEAR COMPANY, OF
SAME PLACE.

DOUBLE TRUCK.

SPECIFICATION forming part of Letters Patent No. 639,639, dated December 19, 1899.

Application filed June 7, 1897. Serial No. 639,701. (No model.)

To all whom it may concern:

Be it known that we, WALTER H. WILKINSON and HORACE L. GEE, citizens of the United States, residing at Kingston, in the county of 5 Ulster and State of New York, have invented new and useful Improvements in Double Trucks, of which the following is a specification.

The objects of our improvements are to 10 provide a swivel-bolster of a double truck with elements which give it great strength, to provide two-way bolster-guiding pedestals which are secured to the side frames of the truck by means which strengthen the 15 union of the bar members of the side frames and thereby stiffen the latter, to provide with the side frames guiding-pedestals having open upper ends which receive in one line of direction from above the outer ends of the 20 bolster and in a transverse line of direction the elastic end support of the same, to provide with bolster-guiding pedestals devices by which the elastic supports of the bolster may be held at a preferred tension while least 25 loaded and be prevented from imparting to the bolster and the car seated thereon a rebound beyond a predetermined limit, and to provide mechanisms by which the weight on the bolster may be transferred through elastic 30 supports to the side frames of the truck at points thereon near the axle-bearings.

Other objects and advantages of the invention will be fully understood from the following description and claims, when taken in connection with the annexed drawings, in which—

Figure 1 is a plan of our improved truck. Fig. 2 is a side elevation with parts in section. Fig. 3 is an end view. Fig. 4 is a sectional view taken at line 2 in Fig. 2. Fig. 5 is a view 40 of a brake-shoe and adjuncts thereto with parts in section. Fig. 6 is a section view at line 2 in Fig. 5. Fig. 7 is a section at line 3 in Fig. 2. Fig. 8 is a section through the bolster, taken at line 4 in Fig. 4. Fig. 9 is an 45 elevation of the bolster, on an enlarged scale, with parts in section and illustrating our preferred form of its construction. Fig. 10 is a plan of this preferred bolster. Fig. 11 is a section taken at line 5 in Fig. 9. Fig. 12 is a 50 side elevation of the bolster-spring-housing block detached from the end of the bolster.

Fig. 13 is a sectional view of the bolster, taken at line 6 in Fig. 9. Fig. 14 is a side elevation, part in section, of the middle portion of a side frame with two-way bolster-guiding pedestal, 55 bolster therein, and elastic support between the latter and said truck-frame. Fig. 15 is taken at line 7, Fig. 14. Fig. 16 is a side elevation illustrating an elastic support of modified form imposed between the truck- 60 frame and bolster.

Similar letters of reference refer to similar parts throughout the several views.

In the drawings, A A are the wheels of the truck, B B the axles, and C C the journal-bearing housings, and with these above-named parts we prefer to employ side frames D D, 65 comprising each the parallel-bar frames D' D' and housing-pedestals D² D² and secured together by suitable end bars E E by means of 70 coupling-pieces and rivets, so as to produce a rigid truck-frame. Our preferred truck-frame, comprising at each side the said two parallel-bar frames and pedestals, is of the kind known to the trade as "double-diamond" truck- 75 frame and composed of the upper bar members a, lower middle bar members a', and lower end bracing members a² a², and the axle-housing pedestals D² D², arranged between the respective parallel pairs of said bar members a, a', and a² at equal distances from the middle of the truck-frame by rivets, which are hot driven and headed. Although these double-diamond side frames may have their 80 bar members to cross each other, yet we prefer to arrange and form them in their middle portions of bars a and a', as shown in Figs. 2, 14, and 15, in which said middle portions are run horizontal and parallel and set edge to edge, so as to unitedly produce a depth of 90 frame equal to two widths of the said bar members, with each reinforcing and stiffening the other.

F F are two-way bolster-guiding pedestals, one at each side of the truck-frame and 95 mounted each on the upper side of the same at points midway between the pedestals D² D² and having a secure connection with the parallel bar-frames D' D'. Although these bolster-guiding pedestals may in some of their 100 portions be differently formed, so as to adapt them for connection and use with truck-

frames of other modifications of form, yet our preferred form of construction of said pedestals F is shown in Figs. 1 and 2 and in enlarged scale in Figs. 14, 15, and 16. These figures show the two-way bolster-guiding pedestal F to comprise the four upwardly-projected bolster-guiding elements $c c' c' c'$ set in pairs, one pair cc outside and the other pair $c' c'$ inside and set at a distance from the outside pair a little greater than the width of the spring or elastic support S, Figs. 1 and 15, which is received between them, while the guiding elements in each pair cc and $c' c'$ face each other and are set apart to a distance adapted to nicely receive the outer ends of the bolster and the end adjuncts thereof, as shown in Figs. 1, 2, 14, and 16. These guiding elements $c c'$ have integral with them the downwardly-projected side webs $d d$, which are set apart, outside measure, to a distance equal to the distance, the parallel bar members $a a$ and $a' a'$ are set apart, so as to be nicely received between them, as shown in Figs. 4 and 15, and these webs $d d$ are integral with the tying-sleeves $e e$, which connect said webs and have their perforations e' continued through said webs, so as to nicely receive the rivets or bolts which may be employed for rigidly securing the bolster-guiding pedestal with the bar members a and a' , as shown. For relieving the rivets e^2 from shearing strain these pedestals have integral with their outer and inner webs $d d$ the outwardly-projected horizontal flanges ff , one below and the other above, and between which the bar members $a a'$ of the side frame are nicely received, so as to be reinforced in their union by the bearing of the respective flanges ff on the respective edges of said bar members, as in Figs. 4, 7, 14, 15, and 16. The upper end of this two-way bolster-guiding pedestal is made open from above, so that an outer end of the bolster and the elastic supporting device connected therewith may at will be introduced from above to between the respective coacting pairs of guiding elements $c c' c' c'$ in said pedestal, as illustrated in Fig. 1, in connection with Figs. 2, 4, 14, 15, and 16. The upper end of each guiding element in the respective pairs $c c'$ is provided with perforation c^2 , adapted to receive a suitable spring-keeper, which may consist of a single piece made in the form of a pin or key, yet we at present prefer this keeper to consist of two parts and comprising the sleeve c^3 and bolt c^4 , Figs. 14, 15, and 16, which will be herein-after more fully referred to.

G is a bolster mounted on elastic supports H H and arranged with its end portions in the two-way bolster-guiding pedestals F F. This bolster is at the middle of the truck and is arranged transversely to the side frames of the same, with its king-bolt hole g relatively midway between said side frames. The elastic supports H may be of any suitable form of construction and parts and are arranged relatively transverse to the bolster and se-

cured to the respective ends of the same by bolts, clips, or their known equivalents, so that while each outer end portion of the bolster is arranged between two pairs of the guiding elements $c c'$ of the two-way bolster-guiding pedestals F the elastic supports, being in the transverse, will be below and arranged between the pairs of guiding elements cc and $c' c'$, as shown in Fig. 1. By this arrangement the bolster will hold by its sides with the said pedestals for moving the truck when a draft is applied to said bolster, or said pedestals will hold with the bolsters when the draft is from the truck and communicated to the bolster, while at the same time the elastic supports H will be held by the said pedestals for preventing the bolster having an end-wise movement in relation to the truck. 85

Although the bolster G employed in connection with the above-described two-way bolster-guiding pedestals F and the elastic supports H may be made with any preferred suitable construction and consist of one or more pieces, yet we at present prefer the bolster be made with a truss-form construction, of which two forms are shown, one in Figs. 3, 4, and 8 and the other in Figs. 9 and 10. 90

In Figs. 3, 4, and 8 the truss-form bolster 95 is shown to be comprised of the channel-iron top-bar member G', the truss flat-bar member G², queen-posts G³ G³, and king-bolt post G⁴. The truss flat-bar member G² is shown to be secured by its outer end portions to the outer end portions of the channel-bar member G' by rivets g', while the said queen-posts are shown to be in the form of vertical sleeves, one at each side of the king-bolt post G⁴, secured from moving by the binding-bolts g² g², 105 binding the bar members G' G² and said queen-posts rigidly together. At each end of this bolster is secured from the lower side of its channel bar member G' spring-block g', Fig. 4, which block also serves as a wear or 110 guide block between the guiding elements $c c'$ of the pedestal F.

Secured by suitable bolts to the bolster at the middle of its length is the usual cup-form coupling-plate I, having its central perforation i coincident with the vertical perforation in the king-bolt post G⁴, and also secured to this bolster at points near their outer ends are the wearing-plates J, which may be of any suitable form of construction, yet we prefer to use wear-plates of the kind known as "cushion" or "elastic" wear-plates. 115

In Figs. 9 and 10, taken in connection with Figs. 11, 12, and 13, we show our preferred form of trussed bolster. In this preferred 125 form of construction of the bolster G the said Figs. 9, 10, 11, 12, and 13 (all taken in connection) show it to be comprised of the channel-iron top member G', the two parallel truss-bar members G⁵ G⁶, the central block J', comprising the queen-posts G³ G³ and king-bolt post G⁴, similar to those shown in truss-form bolster first above described, but made integral with the horizontal upper web j and ver-

tical lower web j' and bearing-flanges j^2 , all of which comprises our preferred members in said central truss-block J' , and with said members $G' G^5 G^5$ and central truss-block J' are shown to be employed the spring-block members K , one at each end of the said bolster, Figs. 9 and 10. The preferred form of construction of these spring-block members is shown in plan by dotted lines in Fig. 10, by side elevation in Figs. 9 and 12, in its rear end view in Fig. 13, and in its front end view in Fig. 14. These spring-block members shown in the said several figures comprise each a single piece of metal and include in the piece the spring-seating-block member k , front and rear guiding members $k' k^2$, horizontal web members k^3 , extended from the upper portion of the rear guiding member k^2 , and the vertical web member k^4 , extended down from the horizontal web k^3 and rearward from said rear guiding member k^2 , all integral and preferably made of cast-steel or other tough metal. These spring-block members are applied to the outer end portions of the channel-bar member of said bolster and against the lower side of the horizontal web portion of the said channel-bar member G' and are secured thereto by rivets $l l$, Figs. 9, 10, and 13, while the outer ends of the parallel truss-bar members $G^5 G^5$ are rigidly secured to the web member k^4 by rivets l' , which rivets l' , together with rivets l through horizontal web member and spring-block member, are driven and headed while red-hot. The central block member J' of this preferred truss-bolster is arranged between the channel-bar member G' and two parallel truss-bar members $G^5 G^5$, with its upper horizontal web j seated in the channel of member G' and has bearing against the horizontal web portion of the same, with its edges against the inner sides of the vertical web portions of said member G' , as shown in Fig. 11, while the bearing-flanges j^2 , Figs. 9 and 11, bear on the upper edges of said parallel-bar members $G^5 G^5$, and the vertical lower web j' is held between said two members $G^5 G^5$ and rigidly secured therewith by rivets j^3 , driven and headed while hot. Binding-bolts J^2 , passing through the horizontal web of the channel-bar member G' and the queen-posts $G^3 G^3$ in said block J' , are shown to hold said parts rigidly secured together and also holding the coupling-plate I , secured central in the said bolster.

The elastic support H for bolster G may be, as above stated, of any suitable form of construction which will adapt it to serve to support said bolster from the truck-frame in an elastic manner and be held between the guiding elements of the bolster-guiding pedestals, and they may each be made to comprise the stiff horizontal bar h , Fig. 16, and spiral springs $h' h'$, having spring-seats h^2 between and having also spring-seats h^3 below, secured or connected with suitable members of each side frame of the truck and provided

with retaining-bolts h^4 . We at present give preference to elastic supports H for bolster G made each in the form of a half-elliptic spring, which is formed of several steel plates h^5 , Figs. 1, 2, 9, 14, and 15, as is the general practice for the construction of this class of spring. The outer ends of this half-elliptic form of elastic support H have their end bearing-seats, as h^6 , made secure to suitable members of the truck-frame at points near the housings of the axle-journals, yet we prefer to form said bearing-seats h^6 integral with the side flanges of the housing-pedestal members D^2 of the truck-frame, as shown in Figs. 1, 2, and 14, so that the load carried by the bolster may be distributed on the truck-frame at points which will be relatively and uniformly near the journals of the axles of the truck-wheels, as shown in Figs. 1 and 2.

Although wear-plates, as J in Figs. 1 and 2, are omitted from the trussed bolster in Figs. 9 and 10, yet it is to be understood that they are to be employed therewith for steady-ing the car-body which may be mounted thereon.

The bolster G and the elastic supports H being secured together and placed in position in the two-way bolster-guiding pedestals F , as above described, while under the normal condition of the spring elements embodied in said elastic supports, resting on their bearings connected with the side frames of the truck and while not under a load or pressure from any source whatever, will be held up as to dotted lines x and z in Figs. 1, 14, and 16, which lines are above the plane said bolster and its elastic supports may stand at when bearing their minimum load, which is illustrated by the full lines said bolster and spring supports are shown at in said figures.

In our practice for assembling the above-described parts and devices ready for use we compress the elastic supports H by a force about equal to that corresponding with the minimum weight or load said elastic supports may bear when ready for active service and for receiving additional weights, as usually attend such service. Although such compression may be effected and kept constant on said elastic supports by any suitable devices, yet we prefer to employ spring-keepers which comprise each a sleeve c^3 and bolt c^4 , Figs. 14, 15, and 16, with the sleeves arranged between the guiding elements $c c'$ and the bolt passing through perforations c in said guiding elements and said sleeve when the latter is in place and at the upper side of the elastic support or a block, as c^5 , Figs. 14 and 16. A screw-threaded nut on the said bolt keeps the bolt in place and causes it to serve as a tying device for holding the guiding elements $c c'$ from spreading in either direction when lateral strains from swaying of the car-body (not shown) are exerted through the bolster and said elastic supports on said two-way bolster-guiding pedestals F .

Having described our invention, what we claim, and desire to secure by Letters Patent, is—

1. The bolster-guiding pedestal F adapted to be mounted upon a side frame, of a truck, and provided with separated upwardly-projected guiding elements arranged in pairs as c c', which are adapted to receive a spring-keeper and provided with a downwardly-projected web adapted to be rigidly secured to the side frame it may be mounted on, of spring-keepers adapted to hold with each pair c c' of said guiding elements, and also adapted to hold compressed an elastic support of a bolster 15 which may be between said guiding elements when in place in the truck, substantially as set forth.

2. The bolster-guiding pedestal F adapted to be mounted upon a side frame of a truck 20 and having the upwardly-projected guiding elements c c c' c' arranged in pairs and having integral with the same the downwardly-projected webs d d tying-sleeves between said webs and flanges f f, substantially as set forth.

25 3. The combination with a double truss-form side frame of a truck, of a bolster-guiding pedestal having upwardly-projected guiding elements c c' integral with webs d d, which are tied by rivet-receiving sleeves e and 30 flanges f, of binding rivets or bolts holding the said side frame rigidly secured with said sleeve-tied webs of said pedestal, substantially as set forth.

35 4. The combination with the two pairs of bar members a a' of a double truss-form side frame of a truck, of the bolster-guiding pedestal F having upwardly-projected guiding elements c c' arranged in pairs and open above, and having integral therewith flanges f seating on the edges of said bar members 40 and double webs d d tied together by sleeve-form ties and arranged between said pairs of bar members and rivets or their known equivalents rigidly holding said bar members between said flanges f and against said webs d d, substantially as described.

45 5. In a double or swivel truck, the combination with the bolster-guiding pedestal F mounted upon the side frames thereof, and 50 having upwardly-projected guiding elements c c' in pairs, of a trussed bolster comprising an upper channel-bar member, truss-bar member secured by its end portions to the end portions of said channel-bar member, and 55 queen-posts and a king-bolt post secured at the middle of length of said connected chan-

nel-bar and truss-bar members, and binding-bolts securing said queen-posts in place from shifting, substantially as described.

6. In a double or swivel truck a trussed bolster formed by the combination with the upper channel-bar member and the double lower truss-form bar members, of a central block comprising two queen-posts which are integral with horizontal and vertical webs 65 which are respectively secured to said upper and double lower bar members of the bolster, and the spring-block members rigidly secured to the outer ends of both said upper and lower bar members, substantially as described. 70

7. In a double or swivel truck, a truss-form bolster formed by the combination with the upper channel-bar member and the two lower truss-form bar members of a central block which comprises a king-bolt post, a piece comprising a horizontal web and a vertical web member all integral, and the spring-block members secured to the lower and upper bar members of the bolster, substantially as and for the purposes set forth. 75

8. In a truss-form bolster, the central block J' comprising two queen-posts, a king-bolt post, horizontal upper web and lower vertical web, all integral in combination with the upper channel-bar member and double lower 85 truss-form bar members, and the spring-blocks secured to the outer end portions of said bar members of the bolster substantially as set forth.

9. In a truss-form bolster, the spring-block member K having integral in it the spring-seat k', horizontal web member k³ and vertical web member k⁴ the two latter adapted to receive rivets substantially as set forth for purposes described. 90

10. In a double or swivel truck, the combination with a bolster-guiding pedestal, mounted upon the upper side of a side frame of the truck, and provided with upwardly-projected guide elements c c', of the spring-block K having spring-seat member k, front and rear guide members k' k', horizontal web member k³ and vertical web member k⁴ all integral and secured to the outer end of a bolster which is adapted to work loosely in said 100 guiding-pedestal and is supported by elastic supports, substantially as described. 105
